X-RAY TUBE

Zed J. Atlee, Elmhurst, Ill., assignor to General
Electric X-Ray Corporation, Chicago, Ill., a cor-
poration of New York

Application April 25, 1941, Serial No. 390,322

7 Claims. (Cl. 250—148)

This invention relates in general to rotatable devices and has more particular reference to rotatable structures enclosed in sealed envelopes, the invention pertaining especially to an improved rotatable anode structure for use in X-ray tubes.

An important object of the present invention is to provide a rotating structure of the character mentioned, having a magnetic brake formed and arranged therein and operable normally to check rotary movement of the device; a further object being to form the braking means as a permanent magnet built into the rotary device and the mounting on which it is carried.

Another important object is to provide an improved braking system for controlling the rotation of a rotary anode in an X-ray tube.

Another important object resides in providing an improved mounting structure for a rotary device of the character mentioned; a further object being to form the mounting as a hollow pedestal within which is journaled a turnable spindle carrying the rotatable device, whereby the pedestal may form a stationary mounting for carrying the magnet or other auxiliary equipment in position to co-operate with the rotary device; a further object being to turnably support the carrying spindle in preferably roller bearings disposed within the hollow pedestal; a still further object being to provide means on the pedestal for lubricating the bearings therein and to control the application of lubricant from a position outwardly of the spindle.

Another important object is to provide for the accomplishment of the foregoing in a structure in which the rotary device comprises a tubular skirt portion embracing and enclosing not only the support pedestal but also all of the mechanism and auxiliary equipment mounted thereon.

These and numerous other important objects, advantages, and inherent functions of the invention will become apparent as the invention is more fully understood from the following description, which, taken in conjunction with the accompanying drawing, discloses a preferred embodiment of the invention.

Referring to the drawing:

Figure 1 is a sectional view through an X-ray tube provided with a rotating anode embodying my present invention; and

Figures 2 and 3 are views taken, respectively, along the lines 2—2 and 3—3 in Figure 1.

To illustrate my invention, I have shown on the drawing an X-ray generator 11 comprising spaced-apart cathode and anode means 13 and 55

15 enclosed within a preferably glass envelope 17. The anode 15 is of the rotating type, being turnably supported for rotation on mounting means 19 which, in turn, is supported on the envelope 17 at one end thereof. As shown, the envelope 17 has an envelope extension 21 within which the anode 15 is snugly disposed, the envelope having a re-entrant sleeve-like portion 23 forming an annular space 25 between the envelope extension 21 and the re-entrant portion 23.

The mounting means 19 comprises a pedestal having a stem-like portion 27 extending outwardly of the envelope and a portion 29 extending within the envelope. The anode 15 is rotatably mounted on the portion 29, which is preferably hollow; and the pedestal is sealed to the envelope at the re-entrant portion 23, which defines an opening in which the pedestal extends. 20 To this end, the pedestal is provided with an annular shoulder 31 carrying, sealed thereon, a plate or disk 32 having a cylindrical rim member 33 sealed at one end to the marginal edge of the disk 32, the opposite end of the rim member 25 providing an annular edge forming a glass-to-metal seal 34 with the envelope at the inner end of the re-entrant envelope portion 23. This seal 34 supports the pedestal and the anode thereon in position embraced by the envelope extension 30 21. The hollow pedestal portion 29 defines an axial cavity 35 extending within the pedestal and opening at the end thereof within the envelope, and the anode 15 is journaled on the inwardly extending portions of the pedestal.

35 It should be understood that X-ray generators function to produce X-rays in response to the activation of the anode by electronic action established by the operation of the cathode 13, said electronic action consisting of the impingement of electrons emitted by the cathode upon a target 41 forming a part of the anode 15. Electronic impingement on the target results in the generation of relatively large quantities of heat at the target, which is dissipated thence through the body of the anode 15. When in operation, the temperature of the X-ray generator, and particularly the anode, may be of the order of 500° centigrade and above. It should be understood, also, that X-ray generators are conditioned for operation by exhausting from the envelope substantially all gaseous and other impurities by evacuating the envelope, as by means of a molecular exhaust pump, and finally sealing the envelope in evacuated condition.

It is desirable that the target 41 be rotated at

high speed in order to minimize the danger of over-heating the target itself at the point of electron impact. Considerable difficulty is encountered in providing suitable support for the rotating element 15, since it is desirable to support the element in precise alignment for high speed rotation substantially without vibration throughout extended service periods. It is not feasible to utilize ordinary lubricants which evaporate, under the excessively high temperature and excessively low pressure conditions necessarily maintained within the envelope, and therefore will not remain in the bearings but will dissipate throughout the envelope, thus not only robbing the bearings of lubrication, but also impairing vacuum conditions in the tube and rendering the same inoperative.

My present invention includes the provision of means for lubricating the bearings in a manner avoiding the aforesaid difficulties, so that the device 15 may be supported for high speed, substantially frictionless rotation within the envelope.

Under ordinary circumstances, an X-ray generator remains in operation for but short intervals of time, of the order of a few seconds, sufficient to accomplish the making of X-ray photographs. During such operation, the anode 15 is first brought to operating speed, as by means of a suitable motor, at which time the tube energizing system connected with the anode and cathode is actuated for the production of X-rays through the electronic impingement upon the target 41, the X-ray exposure being made while the tube is in operation. Immediately upon the completion of the exposure, the tube energizing system is disabled and the anode driving means is de-energized. As a safety precaution, means is ordinarily provided for insuring that the anode is rotating at full operating speed throughout the period of the tube energizing system. The anode, being of appreciable mass and supported on substantially frictionless bearing means, will tend to continue to rotate for an appreciable interval, of the order of several minutes, even after the anode driving means has been de-energized, there being little, if any, braking effect due to windage in the evacuated envelope.

Naturally, the service life of an X-ray tube having a rotating anode, to some extent, depends upon wear in the anode bearings, which is relatively rapid in X-ray tubes in which the bearings are subjected to the excessive heat conditions developed as a result of the operation of the device. The service life of the bearings is further shortened due to the fact that lubrication, in the ordinary sense, cannot be provided where bearings are in operation under the substantial vacuum conditions prevailing in X-ray tubes. In order, therefore, to conserve the bearings and to prolong the useful life of the X-ray tube, I provide not only for adequately lubricating the bearings, but also provide means in the anode structure itself for rapidly braking the anode to stand-still condition in order to reduce coasting time and resultant bearing wear after the termination of the period of useful rotation.

As shown in the drawing, the anode 15 comprises a cylindrical body 39 having an open end extending in the annular envelope space 25 in position to encircle the seal 34. The anode thus forms a shield for protecting the seal 34 from deterioration through impingement of stray electrons thereon. The opposite end of the anode body is enclosed and affords a mounting

for the target 41. In the illustrated embodiment, the target 41 comprises an annular ring of suitable target material, such as tungsten, which is embedded and secured in the preferably copper body of the anode 15. The anode body is formed with a groove 42 at the marginal edge of the end wall of the anode outwardly of the outer edge of the ring 41, and a suitable strengthening rim 44 is preferably set into the groove 42. The ring 44 may comprise a tungsten copper composition and is joined to the outer edge of the target ring 41 and to the main copper body of the anode at the surfaces of the groove 42. The strengthening ring 44 preferably comprises a sponge-like mass of tungsten or other suitable material, such as tantalum or molybdenum, characterized by high melting temperature, with a preferably cuprous, tough, crack-resisting alloy filling the pores of said sponge-like mass. As a filler, I may use a predominantly copper alloy containing a heat hardening constituent, the alloy also permissively and preferably containing a deoxidating medium to promote "wetting" with tungsten. Any suitable hardening medium, such as chromium or cobalt, may be employed as the heat hardening constituent, and I may use beryllium, lithium, boron, calcium, or other suitable "wetting" agent. A satisfactory alloy formula is:

	Per cent by weight
Copper	98.5
Beryllium	1.0
Calcium	0.5

The ring 44 may be made by pressing a homogeneous mixture of tungsten and the copper alloy in powdered condition to form a pressed ring. This ring may then be sintered to form the finished ring of appropriate shape. The joining of the parts 39, 41 and 44 may be accomplished as a casting process by pre-forming the target ring 41 and then the reinforcing ring 44, then assembling the parts in a suitable mold and casting the copper body 39, which may comprise an alloy similar to that used as a filler in the ring 44. The material of the ring thus has a coefficient of thermal expansion intermediate that of the target and body so that the tendency for cracking between the target and the body is greatly minimized.

The pedestal portion 29 extends within the cylindrical body of the anode and carries anode bearings comprising, in the illustrated embodiment, a pair of roller bearings 43 and 45 in spaced-apart position on the pedestal portion 29. Each bearing comprises an outer race secured preferably in the hollow pedestal, and an inner race secured on and thereby supporting a spindle 47, suitable roller members being conventionally retained between the inner and outer race portions of the bearings.

The spindle 47 may, of course, be secured in the bearings in any suitable or preferred fashion, although I have shown the same as being formed with threaded portions receiving clamping nuts for clampingly securing the inner bearing races in spaced relationship on the spindle 47, the outer races of the bearings 43 and 45 being secured in the cavity 35, the outer race of the bearing 43 being secured in a seat 49 formed near the bottom of the cavity, said race being held in said seat by a spacing tube 51, one end of which engages the outer race of the bearing 43 to hold it on the seat 49. The other end of the tube 51 forms a seat for receiving the outer race of the bearing 45, which is held in place by a clamping

tube 53 having a flange portion 55 secured to the inner end of the pedestal portion 29 as by means of holding screws 57. The spindle 47 is thus journaled for rotation in the bearings 43 and 45 which are mounted on the pedestal portion 29. The stem 47 has an end formed with a flange 59 outwardly of the open end of the pedestal portion 29. The anode 15 is secured on said flange 59 by means of an annular mounting frame 61, which is formed at one end for clamping on the flanged end of the stem 47. To this end, the frame 61 has an end wall 63 formed with an opening defined by a boss 65 for receiving the end of the stem 47 outwardly of the flange 59, the frame 61 being secured on the stem 47 by means of a bolt 67 threading into the stem 47 and having a head overlying the boss 65 to thereby clamp the wall 63 upon the flange 59. The frame 61 comprises cylindrical portions preferably formed integrally with the wall 63 and extending thence outwardly of and encircling the pedestal portion 29, said frame 61 having an enlarged annular portion 69 adapted snugly to extend within the cylindrical portion 39 of the anode 15, which is formed with a shoulder 71 defining a seat for receiving the frame portion 69, the anode being anchored on the frame as by means of holding screws 72.

In order to lubricate the bearings, I provide for the application thereto of a lubricating medium which has a vapor pressure sufficiently low so that it will not evaporate from the bearing under the conditions of temperature and pressure prevailing within the envelope. To this end, I may utilize, as a lubricating medium, a material such as barium, caesium, strontium, cadmium, chromium, copper, silver, aluminum, iron or nickel, which have a vapor pressure of the order of 10^{-6} mm. of mercury at temperatures of the order of 200° centigrade, whereby the lubricating medium may not migrate from a treated bearing operating under low pressure and high temperature conditions. In practicing this phase of my present invention, I provide for applying the selected lubricating medium in film-like form upon the bearings after the same have been assembled in place and the envelope evacuated. The selected material or materials are applied upon the bearing surfaces by vaporizing the same and directing the vaporized material upon the bearing surfaces to be treated, whereby to condense the vapor as a thin film upon the working surfaces of the bearings. The deposited material forms an alloy with the material of the bearings, which may be any suitable ferrous material, whereby is formed an alloy film having desired lubricating properties.

Vaporization and delivery of the bearing material upon the surfaces to be treated may be accomplished in any suitable or preferred manner. A supply of the material, for example, may be positioned in a capsule or container, having an opening facing the surfaces to be treated, and the material then heated in the capsule, as by the passage of an electric current, in order to vaporize the material within the capsule and blow the resulting vapor from the capsule and onto the surfaces to be processed. The bearing material may be formed as a filamentary wire in which the desired lubricating medium is incorporated and vaporized upon the bearing surfaces by passing an electric current through the wire. I prefer, however, in treating bearings for use in X-ray generators, to employ a hollow filamentary wire of iron or nickel containing, 75

within the hollow wire, a quantity of lubricating material such as barium, the hollow wire being weakened by reducing its wall thickness along a side of the wire facing the bearings to be treated.

- 5 By passing an electrical current through the wire, the material therein may be vaporized and vapor products projected through the weakened wall section upon the bearing surfaces.
- As shown in the drawing, the pedestal portion 29 and the spacing tube 51 are cut away to form openings 73 and 75, respectively, adjacent the bearings 43 and 45. In these openings are disposed loops 77 and 79 of hollow wire containing lubricating material, said loops 77 and 79 being disposed with weakened wall portions facing the bearings 43 and 45. One end of each loop is electrically connected, as at 81, on the pedestal portion 29, the other end of each loop being electrically connected, as at 82, with conductors 83 which extend outwardly of the envelope through ducts formed in the plate 32, said conductors being hermetically sealed and electrically insulated in said ducts by glass-to-metal seals 85. By connecting a suitable source of electrical potential between the outwardly exposed end 27 of the pedestal and either or both of the conductors 83, an electrical heating current may be caused to flow through the wire in order to raise the temperature thereof to a point at which the lubricating material therein may be vaporized, and, as heretofore described, expelled through the weakened wall portion of the loops and onto the bearings. The bearings may thus be lubricated, and the quantity of lubricating material applied to each bearing may be regulated by controlling the activating current delivered through each loop. Each loop, furthermore, may be supplied with sufficient lubricating medium to enable re-lubrication of the bearings from time to time 40 during the service life of the device.

In order to provide for making the anode to bring it rapidly to stand-still condition from operating speed, I provide magnetic means on the stationary and rotatable portions of the anode support adapted to function as a magnetic brake. The magnet may, of course, be applied on either one of the relatively rotatable members in position to magnetically influence the other, and, as shown in the drawing, the brake 45 comprises a magnet 87 fastened on the stationary pedestal in position to magnetically co-operate with a member of magnetic material on the anode, this co-operating member of magnetic material conveniently comprising the anode support frame 61, which may be formed of steel or other suitable material adapted to form a magnetic circuit with the magnet 87.

As shown, the magnet 87 comprises a bar of permanently magnetized material characterized by the ability to retain magnetic properties at the operating temperature of the anode. Alnico is a suitable material for the purpose. The permanent magnet 87 is anchored in a slot 89 formed longitudinally in the external surfaces of the pedestal portion 29, suitable fastening straps 91 being employed to anchor the bar in the slot. The bar 87, at its opposite ends, is formed to receive the straps 91, the medial portions of which are arranged to form magnet shoes 93 and 95, having surfaces snugly underlying the inner walls of the frame 61, whereby a magnetic circuit, including the magnet 87, the shoes 93 and 95, and the portion of the frame 61 extending between the shoes, will be established. This magnetic circuit will at all times

tend to prevent relative angular movement between the pedestal on which the magnet 37 is clamped and the anode 15 which is secured to the frame 61. This tendency to prevent relative rotation between the parts, of course, is not sufficient to prevent rotation of the anode at operating speed when the anode driving motor is in operation. However, as soon as the anode driving motor is disabled, the magnetic brake, afforded by the permanent magnet 67 and the co-operating frame 61 of magnetic material, will brake the anode to stand-still within a period of the order of a fraction of a minute.

The formation of the frame 61 of steel, in combination with the formation of the anode with a cylindrical skirt of cuprous material embracing the frame 61, enables me to utilize the anode assembly as the rotor of an electric motor having stationary motor windings 99 arranged in annular form and disposed about the envelope extension 21 in which the anode structure is disposed. By energizing the windings from a suitable source of electrical power externally of the envelope, a rotating electromagnetic effect may be established within the envelope portion 21, and the anode thus caused to rotate.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. An X-ray tube having a sealed envelope, a rotary structure in said envelope comprising a support member, a rotary member on said support member, magnetic brake means comprising a permanent magnet on one of said members, and a co-operating element on the other member and forming, with said permanent magnet, a magnetic circuit whereby normally to resist relative angular movement between the support member and the rotary member.

2. An X-ray tube having a sealed envelope, a rotary structure in said envelope comprising a support member, a rotary member on said support member, a permanent magnet on said support member, means on said rotary member and forming a magnetic circuit with said magnet whereby normally to resist relative angular movement between the support member and the rotary member.

3. An X-ray tube having a sealed envelope, a rotary structure in said envelope comprising a support member, a rotary member on said support member, a permanent magnet anchored on one of said members, circuit-forming means an-

chored on the other member and forming a magnetic circuit with said permanent magnet, and magnet shoes on said permanent magnet and extending to form small gaps with said circuit-forming means whereby to establish a magnetic circuit on the support member and on said rotary member tending normally to resist relative angular movement between the members.

4. An X-ray tube having a sealed envelope, a rotary structure in said envelope comprising a hollow support member formed with a cavity having an opening, a stem journaled in said cavity and having an end projecting at said opening, rotatable means secured on the projecting end of the stem and having portions, including portions of magnetic material, spaced outwardly of and encircling said support member, and a permanent magnet on said support member within said embracing portions of magnetic material.
5. An X-ray tube having a sealed envelope, a rotary structure in said envelope comprising a support member, means forming a rotary anode member supported on and having hollow portions embracing the support member, said hollow portions being spaced outwardly of the support member, and magnetic brake means comprising a permanent magnet on one of said members and a co-operating element on the other member and forming, with said permanent magnet, a magnetic circuit whereby normally to resist relative angular movement between the support member and the rotary anode member, said permanent magnet and said co-operating element being disposed within the space defined between the support member and the hollow portions of the anode member.

6. An X-ray tube having a sealed envelope, a rotary structure in said envelope comprising a hollow support member formed with a cavity having an opening, a stem journaled in said cavity and having an end projecting at said opening, a rotatable support frame secured on the projecting end of the stem and having portions, including portions of magnetic material, spaced outwardly of and encircling said support member, a permanent magnet on said support member within said embracing portions of magnetic material, and means forming an anode secured on said rotatable support frame.

7. An X-ray tube having a sealed envelope, a rotary structure in said envelope comprising a support member, rotary means journaled on said support member and having portions, including portions of magnetic material, spaced outwardly of and encircling said support member, said support member being formed with a seat and a permanent magnet secured in said seat in position extending within said embracing portions of magnetic material.
